(57) **CLAIM**

The ornamental design for a rotor and universal joint assembly, as shown and described.

DESCRIPTION

FIG. 1 is a perspective view of a rotor and universal joint assembly;

FIG. 2 is a front elevational view of the rotor and universal joint assembly;

FIG. 3 is a rear elevational view of the rotor and universal joint assembly;

FIG. 4 is a right side view of the rotor and universal joint assembly;

FIG. 5 is a left side view of the rotor and universal joint assembly;

FIG. 6 is a top plan view of the rotor and universal joint assembly; and,

FIG. 7 is a bottom plan view of the rotor and universal joint assembly.

The broken lines in the Figures represent portions of a rotor and universal joint assembly and form no part of the claimed design.

1 Claim, 2 Drawing Sheets
